BAKING PAN

Original Filed Sept. 27, 1928 2 Sheets-Sheet 2

Inventor:
Louis H. Debs,
By Wm. & Wm. Debs.

UNITED STATES PATENT OFFICE

LOUIS H. DEBS, OF CHICAGO, ILLINOIS

BAKING PAN

Original application filed September 27, 1928, Serial No. 308,669. Divided and this application filed October 12, 1929. Serial No. 399,173.

This invention relates to baking pans and more particularly to a multiple-pan construction in which the pans are mounted within a band iron frame having transverse braces at intervals. The present invention is also concerned with a novel form of rivet connection, an improved end protection plate, etc., all of which are more fully hereinafter set forth. The features of invention herein claimed were first disclosed in my application filed September 27, 1928, Serial No. 308,669, of which this is a division.

A suggestive embodiment of my invention is illustrated in the accompanying drawings 15 in the manner following:

Figure 1 is an end elevation of several pans mounted in a unitary frame to produce a multiple-pan structure;

Fig. 2 is an enlarged detail in section on line 2 of Fig. 1 showing one of the connecting rivets as it appears when first set in place;

Fig. 3 which is a similar view shows the rivet after being upset;

Fig. 4 is a detail of a rivet having a convex head, as shown in Fig. 2;

Fig. 5 is a similar view of a rivet having a concave head;

Fig. 6 is a perspective view of a multiple-pan unit having a frame which includes a band iron with which is also associated a pair of protection plates;

Fig. 7 which is a detail in section on line 7-7 of Fig. 6 shows one of the protection plates secured in place;

Fig. 8 which is a detail in section on line 8 of Fig. 6 shows one of the braces which extends between adjacent pans;

Fig. 9 is a sectional detail taken on line 40 9 of Fig. 7; and

Fig. 10 which is a detail in perspective shows the brace construction at one of its ends.

Each of the pans shown is made preferably 45 of sheet metal with a bottom 15, and opposite sides and ends 16 and 17 respectively. At the corners are the usual triangular folds 18 which lie adjacent the ends, as seen in Figs. 2 and 3. The upper edges of walls 50 and ends may be outwardly curled for re-

inforcement and other purposes, as will be presently explained.

A pan produced in accordance with the preceding description may be united in a row with others of like construction, as suggested in Figs. 1 and 6. For this purpose, I utilize a common supporting frame which may include an iron band or strap 20 which is extended along the sides and ends of the pan row. Such a band may have its upper edges 55 rested against the under face of the shoulder formed by the curled edges of the several pans, as shown in Fig. 2, and any appropriate means may be used for securing the band to the pans. An improved fastening for this purpose is suggested in Figs. 2 to 5, wherein I have shown a rivet 21 having a pre-formed head 22 which is curved either convexly as in Figs. 2 and 4, or concavely, as in Fig. 5, the thickness of the head being substantially 60 uniform in either case. Such a rivet may be inserted through a pan adjacent its corners so as to pass through the extra thicknesses afforded by its folds, and also through the band iron frame which is arranged exteriorly thereof. Preferably, a recess or seat 23 65 for the rivet head is prearranged by the use of an appropriate die so that the rivet will initially occupy a position as shown in Fig. 2. Thereafter, when the rivet end is upset, 70 two things will happen: its outer end 24 will be spread, as shown in Fig. 3, and the head 22 will be flattened out to substantially the form which is shown in the same figure. This final flattened form will be reached regard- 75

less of whether the head be initially convex, as shown in Fig. 4, or concave, as shown in Fig. 5. In either case, the flattening of the head will cause a spreading of its edges without any appreciable displacement of the metal. The result of this operation is that the rivet head will be tightly fitted within the recess or seat which is provided in the pan walls for its reception. By this construction 80 the rivet head is seated snugly and with an improved fit within the pan recess, so as to avoid protruding upon the inner face of the pan wall; by this construction also I eliminate any crevice between the rivet head and 85

the pan, thereby obviating possible accumulation of dirt and grease.

It is contemplated that a series of rivet connections, one for each of the folds at the pan ends, will be arranged between the band iron frame and the pans which are mounted therewithin. This means of connection is best illustrated in Fig. 1. Another form of connection between the pans and band iron frame is suggested in Figs. 6 to 10 inclusive to which reference will now be made. The pans there-in shown may be of the general kind already described, in that their edges are curled over to provide their own reinforcement without the aid of any supplementary means, such as a round wire.

As shown in Fig. 6, I position a channel brace 25 of sheet metal having its side walls 26 curled over at 27 and under the curled edges of the pans to which it is connected. By intercurling in this manner the side walls of the brace and the edges of the pan walls, the two parts are interlocked so that the brace serves as a medium of connection between the adjacent pans. As suggested in Fig. 10, at their ends the side walls 26 of the channel brace are curved outwardly at 28 in general conformity with the curvature of the pan corners, these walls stopping approximately flush with the outer face of the pan ends. The horizontal main wall of the brace is desirably formed with elongated slots 29 so as to provide ventilating apertures. The ends of the main wall are initially provided with depending ears 30 adapted to lie approximately flush with the outer face of the pan ends. From these ears one or more lugs 31 are struck outwardly in position for insertion through registering slots in holes in the band irons, the ends of these lugs being thereafter clinched or upset to establish a secure connection between the brace ends and the band iron frame.

At each end of the pan row I may arrange a protection plate 32. As shown, this plate is secured in place by having its upper edge 33 intercurled with the corresponding edge of the adjacent pan side 16 after the manner already described in connection with the brace of Fig. 8. This protection plate may extend downwardly and then inwardly, as shown, to provide a lip 34 which underlies the lower edge of the end pan. In addition, I have shown at each end of the protection plate an ear 35 which is extended laterally along the proximate end walls 17 of the adjacent pan. These ears may desirably be of triangular form and along their upper edges are intercurled with the corresponding edges of the pan end walls 17. A supplementary connection may also be provided, and, as shown, this takes the form of lugs 36 which are outstruck from the ears for extension through registering holes or slots 37 in the

band iron frame. When the ends of the lugs are clinched or upset the connection thus provided becomes fast. It will be noted that the end protection plates constructed as described afford also a protection which extends around the corners of the multiple-pan unit, and that the ears which are fastened to the band iron frame at points remote from the ends of the pan row serve also to secure the end protection plates against movement from the position shown.

The present invention is advantageous in that each pan may be formed with an edge reinforcement which requires no separate or additional parts, a pan of this kind lending itself to a novel and improved securement within a frame which carries other like pans, the means employed in connecting the pans in place being inexpensive, quickly applied, and highly suitable to meet all service conditions.

I claim:

1. A multiple baking pan unit comprising a plurality of like pans the adjacent upper edges of which are outwardly curled, the several pans being arranged side by side in a row, a metal brace between adjacent pans having upwardly extending walls received within and interlocked with the outwardly curled edges of the pans and constituting the sole reinforcement for the pan edges, and a band iron frame for the pans.

2. A multiple baking pan unit comprising a plurality of like pans the adjacent upper edges of which are outwardly curled, the several pans being arranged side by side in a row, a metal brace between adjacent pans having upwardly extending walls received within and interlocked with the outwardly curled edges of the pans and constituting the sole reinforcement for the pan edges, and a band iron frame for the pans having a connection with the ends of the braces.

3. A multiple baking pan unit comprising a plurality of like rectangular pans each having a continuous reinforcement at its upper edge in the form of an outward curl, the several pans being arranged side by side in a row, a metal brace between adjacent pans having upwardly extending walls received within and interlocked with the curled edges and corners of adjacent pans, and a band iron frame for the pans.

4. A multiple baking pan unit comprising a plurality of like rectangular pans each having a continuous reinforcement at its upper edge in the form of an outward curl, the several pans being arranged side by side in a row, a metal brace between adjacent pans having upwardly extending walls received within and interlocked with the curled edges and corners of adjacent pans, and a band iron frame for the pans having a connection with the ends of the braces.

5. A multiple baking pan unit comprising

a plurality of like rectangular pans each having a continuous reinforcement at its upper ends in the form of an outward curl, the several pans being arranged side by side in a row, a metal brace between adjacent pans having upwardly extending walls terminating in outwardly flared portions, said walls received within and interlocked with the curled edges and corners of adjacent pans, a skirt depending from the outwardly flared portions of the braces, and a band iron frame for the pans.

6. A multiple baking pan unit comprising a plurality of like rectangular pans each having a continuous reinforcement at its upper ends in the form of an outward curl, the several pans being arranged side by side in a row, a metal brace between adjacent pans having upwardly extending walls terminating in outwardly flared portions, said walls received within and interlocked with the curled edges and corners of adjacent pans, a skirt depending from the outwardly flared portions of the braces, and a band iron frame for the pans having a connection with the skirt.

7. A multiple baking pan unit comprising a plurality of like rectangular pans each having an unbroken reinforcement at its upper edge in the form of an outward curl, the several pans being connected side by side in a row, an end protection plate at each end of the pan row having angular extensions, said protection plate and its angular extensions having a continuous upper edge received within and interlocked with the curled reinforcement of an end pan at the side, corners and ends thereof.

8. A multiple baking pan unit comprising a plurality of like rectangular pans each having an unbroken reinforcement at its upper edge in the form of an outward curl, the several pans being connected side by side in a row, and end protection plate at each end of the pan row having angular extensions, said protection plate and its angular extensions having a continuous upper edge received within and interlocked with the curled reinforcement of an end pan at the sides, corners and ends thereof, and a band iron frame for the pans having connection with the protection plate.

9. A multiple baking pan unit comprising a plurality of like rectangular pans each having an unbroken reinforcement at its upper edge in the form of an outward curl, the several pans being connected side by side in a row, and end protection plate at each end of the pan row having angular extensions, said protection plate and its angular extensions having a continuous upper edge received within and interlocked with the curled reinforcement of an end pan at the sides, corners and ends thereof, a band iron frame for the pans secured to the protection plate, said se-

curing means comprising lugs on the protection plate and interfitting apertures on the band.

In testimony whereof, I have hereunto set my hand this 8th day of October, 1929.

LOUIS H. DEBS.
